US0D1060370S

(12) **United States Design Patent** (10) Patent No.: **US D1,060,370 S**
(45) Date of Patent: ** Feb. 4, 2025

(54) **MONITOR STAND**

(71) Applicant: **KUNSHAN HONGJIE ELECTRONICS CO., LTD.**, Suzhou (CN)

(72) Inventor: **Xiaojie Chang**, Jiangsu (CN)

(**) Term: **15 Years**

(21) Appl. No.: **35/520,948**

(22) Filed: **Apr. 9, 2024**

(80) **Hague Agreement Data**

Int. Filing Date: **Apr. 9, 2024**

Int. Reg. No.: **DM/237092**

Int. Reg. Date: **Apr. 9, 2024**

Int. Reg. Pub. Date: **May 24, 2024**

(30) **Foreign Application Priority Data**

Nov. 7, 2023 (CN) 202330725397.0

(51) **LOC (15) Cl.** **14-02**

(52) **U.S. Cl.**

USPC **D14/452**

(58) **Field of Classification Search**

USPC D14/451, 452, 376, 217, 447, 224
CPC F16M 11/10; F16M 11/2014; F16M 11/2021; F16M 11/105; F16M 11/041

(57)

CLAIM

The ornamental design for a monitor stand as shown and described.

DESCRIPTION

1.1: Front

1.2: Back

1.3: Left

1.4: Right

1.5: Top

1.6: Bottom

1.7: Perspective

Stand for supporting the monitor.

1 Claim, 7 Drawing Sheets
